INK BOTTLE

Wayne W. Bissell, New Castle, Pa.

Application April 20, 1932. Serial No. 606,503

3 Claims. (Cl. 215—12)

My invention relates to improvements in ink bottles, and it consists in the combinations, constructions, and arrangements herein described and claimed.

5 An object of my invention is to provide an ink bottle having an ornamental casing conforming roughly to the shape of the ink bottle.

Another object of my invention is to provide a casing of the class described consisting of a 10 plurality of tubular members, the color and shape of which may be varied.

Another object of my invention is to provide an ink bottle device having a fountain pen holder forming a part thereof.

15 A further object is to provide an ink bottle having a detachable casing which is provided with a threaded cap and a threaded tubular means whereby the casing is operatively retained in position.

20 A further object of my invention is to provide a casing of the character described, a portion of which may be removed without detaching the remainder of the casing from the ink bottle.

25 A further object of my invention is to provide the combination of an ink bottle and a casing, the casing being provided with means whereby the fountain pen may be held in either upright, angular, or prone position.

30 A further object of my invention is to provide an ink bottle having a casing, the upper and lower portions of the ink bottle and the casing being provided with means whereby the casing may be retained in position, even though a part of the casing is removed from the ink bottle.

35 Other objects and advantages will appear in the following specification, and the novel features of the invention will be particularly pointed out in the appended claims.

40 My invention is illustrated in the accompanying drawing, forming part of this application, in which

45 Figure 1 is an elevational view of one form of my invention in which certain parts are shown sectionally and certain parts are shown broken away,

Figure 2 is an elevational, partly sectional, view of another form of my invention, and

50 Figure 3 is a side elevational view of an ink bottle provided with a casing and means whereby a fountain pen may be held either at the top or the base of the ink bottle; the casing is shown partly in section.

55 In carrying out my invention, I provide an ink bottle 1 and a casing 2. The ink bottle 1 is provided at its base with an outwardly extending

peripheral portion 3, and its upper portion with an elongated threaded neck 4. The casing 2 consists of an interiorly threaded cap portion 5, a tubular neck portion 6, a circular outwardly extending shoulder portion 7, and a plurality of circular band portions, such as for instance, the band portions 8, 9, and 10.

The shoulder portion 7 and the band portions 8, 9 and 10 are each provided with annular shoulders 11 whereby the band portions 8, 9 and 10 may be held in position. The band portion 10 comprises the lowermost part of the casing and it is tapered inwardly, as is indicated at 12, so that it may fit snugly with the peripheral portion 3.

55 The casing shown in Figure 1 may be assembled about the bottle 1 substantially as shown, the peripheral portion 3 and the neck portion 6 holding the intermediate elements of the casing rigidly about the bottle 1.

60 In Figure 2, I have shown an ink bottle 13 having a casing 14 which consists of a cap 15, a threaded neck portion 16, and a body cover portion 17. The neck 18 of the bottle 13 is exteriorly threaded for operatively receiving the 65 interiorly threaded cap portion 15 and the neck portion 16. The body portion 17 is fixedly secured to the bottle 13 by reason of the neck portion 16 clamping the inner part of the body portion 17 against the top of the body 19 of the bottle 13.

70 A swivel joint fountain pen holder 20 is operatively secured to the neck of the bottle in any suitable manner, such as for instance, by a 75 threaded screw 21.

75 In Figure 3, I have shown an ink bottle 22 which is provided at its base with a peripheral abutment 23. The bottle 22 is also provided with an elongated offset exteriorly threaded neck 24. A casing 25 encloses the bottle. This casing 25 consists of an interiorly threaded cap 26, an interiorly threaded neck portion 27, a top body portion 28, a base portion 29, and an intermediate band 30.

80 The top body portion is provided with an offset opening 31 for receiving the neck 24 of the bottle. The base 29 may be provided with a pen or pencil holding recess 32 and the top body portion 28 is provided with a peripheral edge 33 for the purpose of forming a pen or paper clip holding recess. The cap portion 26 is provided with a pen holder 34 which may be retained on the cap in the same manner, as is the pen holder 20 on the cap 15.

85 From the foregoing description of the various parts of the above-described forms of my invention, their use and operation may be readily 90

understood. The ordinary ink bottle is an indispensable necessity to every office and writer, and it is desirable from the viewpoint of convenience that an ink bottle be kept on the desk top or 5 within reach of the pen. The ugly appearance of the bottle, its tendency to become soiled with ink, and its inability to serve any useful purpose other than that of a container are such that the ink bottle is usually hidden away in more or less 10 inaccessible places.

By the provision of an ornamental casing having a water-tight cap connected to the bottle in such a manner that it is impossible to suddenly 15 pull the cap out of the bottle and splotch the desk with ink, the ink bottle is rendered suitable to serve also as a paperweight. The weight of the casing added to that of the bottle makes the combination a really serviceable paperweight.

Each of the casings shown consists of a plurality 20 of elements which are adapted to be operatively connected together. Each of these elements may, if desired, be made in such a color that the device of the invention will be an added attraction to the appearance of any desk top.

25 Each of the sections may of course be made of any rigid metal, molded or crystalline material, such as for instance, gold, silver, bakelite, or cut glass.

Another advantage of making the casing of a plurality 30 of parts is that if one of these parts becomes broken, it can be more economically replaced than could a solid casing. This is of particular importance when the casing is made of precious and semi-precious material.

35 The provision of means for holding pins, paper clips shown herein is not merely a matter of convenience, but also enables the casing to prevent spilled ink from running off the casing onto the desk.

40 I claim:

1. In combination, an ink bottle of the char-

acter described and a casing enclosing the top and the side portions thereof, the ink bottle being provided with an exteriorly threaded elongated neck portion, said neck portion being offset with respect to the vertical central axis of said ink bottle, said casing having a cap portion and a main body portion the top of the main body portion being recessed to hold articles placed thereon, each of said portions being adapted to be threadedly connected to the offset neck portion.

2. The combination with an ink bottle having an elongated exteriorly threaded neck portion offset with respect to the central vertical axis of the bottle, of a casing therefor comprising a lower ring-like member adapted to rest on a portion of the bottle, an uppermost section having threads arranged to engage the threads of the bottle neck, intermediate sections, one of said intermediate sections overlying the main body of the ink bottle and being engaged by the bottom of the uppermost section said last named section constituting a pen tray, and a cap having threads arranged to engage the threads of the neck and to be screwed down onto said uppermost section.

3. The combination with an ink bottle having an elongated exteriorly threaded neck portion offset with respect to the central vertical axis of the bottle, of a casing therefor comprising a lower ring-like member adapted to rest on a portion of the bottle, an uppermost section having threads arranged to engage the threads of the bottle neck, intermediate sections, one of said intermediate sections overlying the main body of the ink bottle and having an upstanding peripheral edge and being engaged by the bottom of the uppermost section, and a cap having threads arranged to engage the threads of the neck and to be screwed down onto said uppermost section.
